UNITED STATES PATENT OFFICE.

GEORGE H. REYNOLDS, OF NEW YORK, N. Y.

PNEUMATIC GUN.

SPECIFICATION forming part of Letters Patent No. 421,312, dated February 11, 1890.

Application filed July 29, 1889. Serial No. 319,025. (No model.)

To all whom it may concern:

Be it known that I, GEORGE H. REYNOLDS, of the city and county of New York, in the State of New York, have invented certain new and useful Improvements relating to Pneumatic Guns, of which the following is a specification.

The invention is intended more especially for guns operated by compressed air of high tension and adapted to throw large projectiles containing high explosives; but it may be of service with other projectiles, and be carried out with a wide range of sizes and may be of various proportions, and may serve with other gases than atmospheric air, and the pressure of the gas may be induced by other than mechanical compression.

The objects sought are simplicity and economy of construction and convenience, certainty, and effectiveness of operation. I have been guided to this by years of experience and practical application of the principles on which such ordnance should be constructed.

I will use the word "firing" in its technical sense as used by military men to define the act of discharging the gun. There is no ignition of powder or other combustible.

I will use the word "air" to designate the large volumes of gas under pressure employed to impel the projectile, and the word "oil" to designate the liquid employed in small quantities, with an excess of pressure in the packings, although various other liquids, as water with glycerine, may in practice be substituted.

What I consider the best means of carrying out the invention are fully described below and shown in the accompanying drawings.

Figure 1 represents the gun and the mechanism for operating it, in side elevation, with the loading-carriage in position to introduce a projectile. In this figure the gun is in a plane parallel reservoir. Fig. 2 is a plan view of one end of the gun-carriage, the hydraulic motor for training the gun, and the ram for elevating it; and Fig. 3 is an end view of the mechanism provided to elevate the gun by hand, showing also the motor for training. Fig. 4 is a plan view of the gun,

with its carriage and the loading-carriage. In this figure the gun has been trained in a plane across the firing-reservoirs. Fig. 5 is an end elevation of the gun-carriage frame, 55 with the trunnion-blocks centered on the pintle, one-half of this view being shown in section. Fig. 6 is a plan view of the above parts, half of the upper parts being taken away. Fig. 7 is a plan view of the breech of 60 the gun, partly in section. Fig. 8 is a corresponding section through a portion in a different plane. This figure is on a larger scale. Fig. 9 is a central vertical section of the pintle, showing the two ducts for conveying hydraulic pressure from the stationary parts of the system to operate the machinery for training and elevating the gun, the other allowing the return of the oil or other liquid after having performed this service. Fig. 10 is a cross-section on the line X X. Fig. 11 is a front view of one of the nozzles on the pintle.

Similar letters of reference indicate corresponding parts in all the figures where they occur.

Referring to the drawings, A designates the central pintle, which is securely fastened by bolts to a substantial foundation. It consists of a hollow casting with liberal apertures, combining the following features: first, 80 as a sufficient and firm center around which the gun trains, receiving the recoil of the gun; secondly, as a passage for the air under heavy pressure from the firing-reservoirs to the gun, and in this respect it is so constructed that the strains resulting from this pressure are self-contained, it being closed at the top and bottom, and, thirdly, serving also for the passage to and fro of the motive fluid from the stationary to the movable parts 90 of the apparatus. The air enters from the firing-reservoirs by the two nozzles A' and issues from it through a number of openings a' which being made around the circumference of the pintle, the pressure is balanced in 95 all directions. To receive the recoil of the gun, the pintle is provided with a heavy flange A², re-enforced by ribs around it. The pintle is also constructed with ducts a' a² for the passage to and from the gun of the oil or 100 other fluids under pressure, by which the gun is trained and elevated. Encircling the up-

per portion of the pintle and resting on the | barrel. This track is shown in plan on Sheet 2, its rails being there marked A'', and in sec- 65
 tional elevation, marked by the like letters, on
 Sheet 1. The projectile-carriage T is made
 with wheels of proper diameters to roll easily
 and naturally on this circular track, and is
 provided with a trough t for safely holding
 the projectile, and with a ram T', running on
 slides and worked by chains running over
 sprocket-wheels, for pushing the projectile
 steadily and without shock into the barrel of
 the gun. The sprocket-wheels are attached to
 70 or cast with gear-wheels, the latter being op-
 erated from a pinion-shaft extending from
 side to side of the carriage and turned by
 cranks in the hands of the men engaged in
 loading the gun. 80

10 portion of the pintle and resting on the | barrel. This track is shown in plan on Sheet 2, its rails being there marked A'', and in sec- 65
 tional elevation, marked by the like letters, on
 Sheet 1. The projectile-carriage T is made
 with wheels of proper diameters to roll easily
 and naturally on this circular track, and is
 provided with a trough t for safely holding
 the projectile, and with a ram T', running on
 slides and worked by chains running over
 sprocket-wheels, for pushing the projectile
 steadily and without shock into the barrel of
 the gun. The sprocket-wheels are attached to
 70 or cast with gear-wheels, the latter being op-
 erated from a pinion-shaft extending from
 side to side of the carriage and turned by
 cranks in the hands of the men engaged in
 loading the gun. 80

15 The yoke, with its load, is capable
 of turning in a complete circle around the
 pintle, and the flow of air is not obstructed
 by this movement, the openings in the pintle
 being at all times in full communication with
 the belt. Securely bolted to this yoke are the
 20 trunnion-blocks B⁴. Each trunnion-block
 consists, mainly, of a pipe b', of suitable
 diameter, rising from the yoke to the gun-
 trunnion, supported by ribs and flanges suf-
 ficient to resist the recoil when the gun is
 25 fired. To receive the trunnions of the gun,
 the pipes swell into and terminate in cham-
 bers b⁵, bored to fit them.

At the breech of the gun the barrel is em-
 braced within the firing-valve casing D⁶,
 30 which, with the breech-block H, is bolted to
 a heavy flange D', cast upon the barrel a lit-
 tle forward from the breech.

D is the barrel. D' is the flange, to which valve-casing D⁶
 35 is bolted, and D⁷ is a piece which I call the
 "breech-ring," surrounding the barrel and
 flush with its end, and to which breech-block
 H is secured. Near the end of the barrel are
 40 openings d, through which air is admitted
 for the purpose of propelling the projectile W.

To elevate the gun to the required angle
 for attaining the range desired for the pro-
 jectile, I use a hydraulic ram, marked Q R in
 Sheet 1, Fig. 1, and in the plan view, Fig. 2, of
 45 same sheet. It consists of a barrel Q, trun-
 nioned at the lower end, where it is carried
 by two trunnions Q' in bearings Q⁴, bolted to
 the channel-bars B³. Within this barrel is a
 50 ram R, having one end formed into a fork,
 each end of which fits into a bearing D¹⁸, se-
 curely bolted to the channel-bars D³, which
 constitute the truss for the barrel. The lower
 55 end of the ram R is formed into a piston
 working in the barrel Q, and provided with
 cup-leather packing. The liquid pressure for
 actuating this ram is introduced through one
 of the trunnions Q'. As it is desirable to be
 60 able to load the gun at any point of the cir-
 cle to which it may be trained, I have pro-
 vided a circular track at such a distance from
 the training center as will bring the projectile,
 mounted on a suitable carriage, into the
 proper position for introduction into the gun-

barrel. This track is shown in plan on Sheet 2, its rails being there marked A'', and in sec- 65
 tional elevation, marked by the like letters, on
 Sheet 1. The projectile-carriage T is made
 with wheels of proper diameters to roll easily
 and naturally on this circular track, and is
 provided with a trough t for safely holding
 the projectile, and with a ram T', running on
 slides and worked by chains running over
 sprocket-wheels, for pushing the projectile
 steadily and without shock into the barrel of
 the gun. The sprocket-wheels are attached to
 70 or cast with gear-wheels, the latter being op-
 erated from a pinion-shaft extending from
 side to side of the carriage and turned by
 cranks in the hands of the men engaged in
 loading the gun. 80

In the drawings I have shown the projectile-
 carriage arranged for loading the gun at an
 angle of eight degrees. This enables the car-
 riage to be lower than it would be if the gun
 were brought to a level for loading. 85

The several devices set forth for training
 are not dedicated to the free use of the public,
 but are made the subject-matter of my applica-
 tion filed July 29, 1889, Serial No. 319,024,
 and the hollow pintle in Serial No. 303,218, 90
 filed March 14, 1889.

I claim as my invention—

1. The combination, with a rotatable pneu-
 matic gun and the circular track concentric
 with the pivot thereof and independent of the
 track upon which the gun travels, of the load-
 ing-car traveling on said track, as set forth. 95

2. The combination, with a rotatable pneu-
 matic gun, of the circular track concentric
 with the pivot of the gun, the loading-car 100
 traveling on said track, the sprocket-wheels
 on said car, the chains running over said
 sprocket-wheels, and a ram carried by said
 chains and adapted to push the projectile
 into the barrel of the gun without shock, 105
 substantially as set forth.

3. The combination, with a pneumatic gun,
 of the circular track concentric with the pivot
 thereof, the loading-car traveling on said
 track, the sprocket-wheels on said car, the 110
 chains running over said wheels, a ram car-
 ried by said chains and adapted to push the
 projectile into the barrel of the gun without
 shock, the said sprocket-wheels carrying gear-
 wheels operated by a pinion-shaft extending 115
 from side to side of the loading-car, and pro-
 vided with suitable crank, substantially as
 and for the purpose specified.

In testimony whereof I have hereunto set
 my hand, at the city of New York, this 24th 120
 day of July, 1889, in the presence two sub-
 scribing witnesses.

GEO. H. REYNOLDS.
